SHUTTLE.

1,252,293.

Specification of Letters Patent.

Patented Jan. 1, 1918.

Application filed April 5, 1915. Serial No. 19,209.

To all whom it may concern:

Be it known that I, JONAS NORTHRUP, a citizen of the United States, residing at Hopedale, in the county of Worcester and 5 State of Massachusetts, have invented certain new and useful Improvements in Shuttles; and I do hereby declare the following to be a full, clear, and exact description of the invention, such as will enable others 10 skilled in the art to which it appertains to make and use the same.

The present invention relates to improvements in shuttles and more particularly to improvements in self-threading shuttles for 15 automatic looms.

When, upon the completion of filling replenishment, the shuttle is shot through the shed toward the filling detector shuttle box and the end of the new filling trails from 20 the delivery end of the shuttle and the filling thread is being drawn down toward the recess in the threading block through which the thread passes into the delivery eye of the shuttle upon the return shot of the shuttle, it sometimes happens that, before the filling has found its way into this recess, the shuttle has boxed on the filling detector 25 side of the loom. In such a case, upon the operation of the filling detector, the filling 30 being the thickness of the shuttle from the surface of the lay, the filling detector fork, instead of being engaged by the filling near the ends of the tines where the slightest pressure tilts the fork, is engaged so far up 35 the tines toward the top of the fork that the pressure exerted by the filling against the tines does not serve to tilt the fork. Consequently on such occasions, there is an unnecessary filling replenishment or a stop- 40 page of the loom. One object of the present invention, then, is to produce a shuttle wherein the filling of a newly inserted bobbin upon the first shot of the shuttle across the lay after filling replenishment is posi- 45 tively drawn down into the recess communicating with the delivery eye and will not remain on the upper surface of the delivery end of the shuttle. This recess being sub- 50 substantially on the same plane with the delivery eye, insures a proper tilting of the detector fork by reason of the filling contacting with it near the ends of the tines.

Sometimes when the filling is drawn into the recess communicating with the shuttle eye on the first shot after filling replenishment, on the return shot of the shuttle the 55 filling pulls out of this recess and a real misthread occurs. Another object of the invention, then, is to produce a shuttle in which the threading block is of such construction that its cooperating parts prevent the filling from escaping from the recess once the filling has been drawn down into it.

The impact of the shuttle against the picker stick sometimes causes a looping of 60 the filling which is thrown forward over onto the delivery end of the shuttle. At such times it often happens that a loop or bight catches on some projecting part of the shuttle, whereupon breakage occurs. A further object of the invention, then, is to produce a shuttle in which it is impossible for 65 a looping of the filling caused in the manner described to result in breakage.

Besides the objects above enumerated, another object of the present invention is to produce a threading block, the simplicity of construction of which conduces greatly to its cheapness of manufacture and its certainty of operation.

In the accompanying drawings illustrating the preferred embodiment of the present invention, Figure 1 is a top plan of the delivery and bobbin holding ends of a shuttle; Fig. 2 is a longitudinal side sectional view of the same partly in elevation; Figs. 3 to 7 are enlarged detail views of the improved threading block, Fig. 3 being a top plan, Fig. 4 an outer side elevation, Fig. 5 a partial inner side elevation, Fig. 6 a front 70 end elevation and Fig. 7 a bottom plan; and Fig. 8 is a transverse sectional view on line 8—8 of Fig. 1.

Before entering upon a description of the illustrated embodiment of the invention, it is convenient first to define certain terms of direction and situation, which will be used in order that the reader may readily apprehend the intended meaning. The words "front," "forward" and "outer," and their 75 derivatives, are used to designate the direction toward or the situation of parts near that wall of the shuttle nearest the fell. The direction toward the shuttle wall

nearest the reed, and the situation of parts which lie adjacent to it, are designated by the words "back," "rear" or "inner" and their derivatives. The delivery end of the 5 shuttle is the "left-hand" end, and the bobbin holding end of the shuttle is the "right-hand" end.

In the illustrated embodiment of the invention the shuttle 10 is, in general, of the 10 usual form and construction, having an elongated bobbin recess 11 and is provided at its thread delivery end with a threading block designated generally by the reference character B. The threading block is kept in 15 place in the shuttle by the screw 12, which passes through the slot 13 formed transversely in the bottom of the block. A piece of felt 14 serves to maintain a tension upon the thread in order that proper selvages may 20 be formed. At the bobbin holding end of the shuttle, bobbin holding springs or jaws 15 are provided which will hereinafter be more particularly described. The thread delivery portion of the shuttle is formed in 25 the following manner: A round hole is bored diagonally from a point near the extremity of the delivery end inwardly or backwardly toward the left-hand end of the bobbin recess emerging opposite the end or tip 16 of 30 the bobbin for accommodating the threading device or block B, which is cylindrical in form. A thread entrance channel 18 is formed by cutting away the material of the shuttle above the block so as to form a slot 35 having widely divergent sides at the end nearest the tip of the bobbin and narrowly convergent sides at its forward end. The sides of the channel are convex and slope toward the threading block, so as to guide 40 the thread down into the threading block. This channel 18 tapers from its wide open mouth near the delivery end of the bobbin to a point near the surface of the front wall of the shuttle body, at which point the front 45 or side wall 22 of the channel terminates and the back or side wall 23 slopes sharply backward and downwardly forming a concave recess 26 overhung by a brow or shoulder 27. This brow or shoulder 27, in co-operation 50 with parts of the threading block serves as a guard to prevent the escape of the filling thread once it has passed down under the beak. From an inspection of Fig. 1, it will be seen that the entrance passage or channel 55 18 is slightly diagonally spiral, its curvature being very slight from its mouth as far as the contracted portion. At this point, a portion of the block forms the front wall of the channel which runs somewhat parallel 60 to the adjacent convergent side of the shuttle and beyond this point the two sides of the channel overlap each other. This peculiar construction of the entrance passage or channel from the top of the shuttle down to 65 the threading block, comprises one of the

features of the present invention and its advantages will be pointed out in the description of the operation of the improved threading device.

The description of the body portion of the improved threading device or block is as follows:— The body portion of the block is cylindrical in form and has throughout its length a tubular chamber or thread passage 30. In the top of the cylinder is cut a spiral 75 slot 31, which conforms in direction with the channel 18 so that a passageway is formed from the top of the shuttle down to the bottom of the tubular thread chamber. The left-hand end of the spiral slot of the 80 threading block or cylinder terminates at the point 32 which lies about under the middle of a shield 20. The sides of this spiral slot run parallel from the point 32 rightwardly to about the middle of the cylindrical body, from which point they diverge slightly. This slight divergence continues gradually as far as a hook-like horn 33. The inner or rear side 34 terminates at the base of the horn and the outer or front side 35 85 plunges helically downward under the end of the horn to the bottom of the cylinder; thence ascending to the point 37 on the rear side adjacent to the right-hand side of the base of the horn. This hook-like horn 33 90 projects laterally outwardly from the top rear wall of the slot 31 and is curved downwardly in conformity with the external surface of the cylinder. The horn is generally triangular in shape and its apex 38 closely 95 approaches the adjacent portion of the opposite side of the slot forming a very narrow strait or passage 39. This horn is the last obstruction met by the thread in its passage downward into the tubular chamber of 100 the threading block. Once the thread has passed through the strait 39, it is practically impossible for it to escape therethrough. Although, strictly speaking, the horn is an obstruction to the immediate passage of the 105 thread into the cylinder, it is so shaped as to afford the least resistance possible and it is so positioned in relation to the other parts of the threading device that the thread is not impeded in passing the point 38, especially as the thread unwinds from the bobbin in the same direction in which the horn extends. (In this connection it is to be noted that in a shuttle used on a left-hand loom the horn would project in the opposite 110 direction unless the bobbins were oppositely wound.)

The shield 20, which is supported on an upward extension or upright 40 on the left-hand end of the outer side of the threading 115 block, constituting, together with the upright, a prolongation of the front shuttle wall 22, slopes downwardly, leftwardly and inwardly and terminates in an arched formation or beak 28. The right-hand portion 120

or spur 21 of the shield projects into a recess in the front of the shuttle side so that the upper surface of the shield is practically a continuation of the surface of the gently sloping declivity of the tapering end of the shuttle side. This construction prevents the filling from catching either on the wood or on the shield. The inner side 25 of the shield 20 acts as a guide to deflect the thread 10 downwardly into the left-hand end of the threading block slot 31. If the thread should not pass immediately from the tip of the beak into the slot 31, or if it should pass into the slot and should afterward escape therefrom, it would be retained in a vestibule or space under the arched beak 28. The shed 42 slopes backwardly and downwardly to the spiral thread slot 31 from the base 43 of the shield 20, so as to facilitate 15 the passage of the thread from the vestibule into the spiral slot. It is to be observed that when the thread is in this vestibule it is deliverable in either direction of movement of the shuttle.

20 A delivery eye entrance slot 44 extends from the end of the spiral slot 31 diagonally forward through the bottom of the threading block to the delivery eye 45. Through this slot the thread is drawn into the delivery eye on the second or return pick after filling replenishment. On the first pick after the filling replenishment the thread lies above the shelf 51 and on the next succeeding pick in the opposite direction the 25 thread glides down the inclined receding end 47 of the upright 40 and around the point of the shelf 51 and passes into the delivery eye entrance slot 44 through which it slides into the delivery eye. The wood of the 30 shuttle is scooped out under the left end of the threading block as far to the right as the forward or front end of the delivery eye slot 44 so as to afford a passage-way for the thread as it is drawn under the shelf and 35 through the delivery eye slot into the delivery eye. A guide pin 46 stands vertically in the left-hand end of the tubular chamber of the threading block, its left side 48 being in line with the center of the delivery eye. 40 This pin forms a wear member or guide which directs the thread to the delivery eye 45. The delivery eye slot 44 opens into the lower right-hand side of the delivery eye 45, and in the usual and regular operation 45 of the shuttle the thread is discharged from the delivery eye either through the right-hand side or the left-hand side of the eye. The point 53 formed by the junction of the delivery eye slot with the eye crosses the 50 bottom of the eye and tends to prevent the thread from escaping therefrom back into the delivery eye slot. In this connection it is to be noted that if the thread, running from the tip of the bobbin, should throw itself out of the slot 31 and extend 55

along the shuttle body to the outside of the upright 40 and thence inward around the end 47 of the upright to the delivery eye, the shelf would tend to prevent dethreading, and that a continued pull upon the thread 70 would rethread the shuttle. This shelf, therefore, constitutes a feature of the invention as it contributes to prevent dethreading of the shuttle due to the overthrow of 75 the thread.

The course pursued by the filling thread as it is drawn into the delivery eye is described as follows: On the first shot of the newly replenished shuttle across the lay, the filling thread first passes into the mouth of 80 the thread channel 18 and almost immediately thereafter into the right-hand end of the cylinder slot 31. The strain exerted upon it then draws the thread against the inner edge 25 of the shield which deflects 85 the thread by the beak 28 into the recess 26. As the thread passes the beak 28, it is received in the left-hand end of the block slot 31. The thread is now entirely within the tubular chamber in the thread cylinder, 90 except that it has not passed the tip 38 of the horn 33. One or two unwindings from the bobbin, however, suffices for it to be brought under the horn. If it is not, the thread, nevertheless, is in deliverable 95 position, even though the shuttle be on its return pick before the thread passes under the horn. The beak 28 of the shield 20, in coöperation with the brow or shoulder 27 of the beak recess 26, effectually prevents the 100 regress of the thread. On the return pick of the shuttle, after filling replenishment, the thread is drawn against the deflector end 47 of the threading block, and inasmuch as this edge recedes downwardly and backwardly toward the entrance of the delivery eye slot 44, the thread glides down this edge 105 47 and is drawn into the delivery eye slot and thence is drawn into the delivery eye 45. The thread obviously has no tendency 110 to be drawn out of the delivery eye while the shuttle is traveling toward the hopper end of the loom. On the next shot of the shuttle away from the replenishing end of the loom, the thread is prevented from escaping through the slot 44 by the delivery eye guard 53, the tip of which projects rightwardly beyond the front side of the 115 guide pin around which the thread is delivered to the eye.

120 Attention is directed to the fact that the bottom of the tubular chamber is in substantially the same plane as the bottom of the delivery eye, so that inasmuch as the filling thread is practically always drawn down to the bottom of the threading cylinder on its first shot across the lay after filling replenishment, the thread is in a plane to be engaged properly by the tines of the detector fork. The tubular chamber of 130

the threading block constituting as it does a receiving recess for the filling thread on the first pick of the shuttle, and this receiving recess communicating as it does with 5 the delivery eye, a construction is provided in which the filling thread is fed out from a recess substantially on the same plane with the delivery eye, during the first shot of the shuttle across the lay after filling 10 replenishment. That is to say, on the first shot of the shuttle the thread has a low delivery position. It will be noted that when the filling thread is not drawn through the delivery eye, the tubular chamber forms a 15 temporary delivery passage for the thread, but when the thread is discharged from the delivery eye, the tubular chamber together with the delivery eye forms an ultimate delivery passage.

20 From the foregoing description it is apparent that the threading block embraced in this invention is one of extreme simplicity and of positive operation. There are no projecting points upon which loops or bights 25 of the thread may catch. An overthrown bight of thread encircling the horn 33, or the beak 28, or the shelf 51, will disengage itself. The thread passage or channel 18, from the top of the shuttle down to the 30 thread chamber of the threading block offers practically no obstruction to the passage of a thread therethrough. The sinuous coöperating sides of the channel serve only to deflect the thread into its temporary and 35 ultimate delivery passage.

The shuttle described above in connection with the improved threading block, is used on a right-hand loom, that is, a loom having the weft replenishing mechanism on 40 its left-hand end. It will be observed that the horn 33 of the threading block is directed toward the front of the shuttle, so that as the filling unwinds toward the front of the shuttle from the bobbin, it follows the 45 direction of the horn, and has no tendency to catch thereon and be drawn over the outside of the horn. Now, inasmuch as it is desirable that similarly wound bobbins be available for use in both right and left- 50 hand looms, it is necessary that the horn project in the same direction in shuttles for both looms. It should also be observed that if the threading block is used in a left-hand loom shuttle, the terms denoting 55 a direction toward either the left or right will be reversed.

The bobbin holding jaws or springs 15 are made of a strip of flat stock, the ends being bent U-shaped, the bottom of the U 60 being somewhat elongated into a narrow neck 55 and receiving between the depressed sides, a block 56 for solidity. The neck 55 of the holding jaws is received in a recess in the bobbin holding end of the shuttle 65 and secured therein by the screw 57. The

parallel sides of the jaws are provided with recesses 59 into which are received the rings on the bobbin in the usual manner for holding the bobbin in operative position. Hitherto, bobbin holding jaws, constructed of 70 flat stock, have lacked the resiliency of the forged and machined jaws, the sides of which taper gradually from their base. The present invention secures this proper resiliency by chamfering the top inside 75 edges of both jaws so that the chamfer tapers gradually from about the point 60 at the base of each jaw to about the point 61, from whence outward to their ends the sides of the jaws run parallelly. From the 80 point 61 the chamfer or bevel proceeds to the ends of the jaws parallel with their top edges. The result of chamfering the jaws in this manner, as it is obvious, is the removal of the greater amount of stock from 85 the extremity of the jaws where the greater resiliency is desired, and the lesser amount of stock from the base of the jaws, where a lesser resiliency and a greater strength are desired. Bobbin-holding jaws constructed 90 in this manner have all the advantages of jaws constructed of forged steel machined into proper shape. Another advantage of the bevel or chamfer on the top inside edges of the sides of the bobbin- 95 holding jaws, lies in the ready entrance it affords to the bobbin during the filling replenishment.

As indicated in the preamble, the present invention is not limited to use in connection 100 with shuttles adapted solely for employment in automatic weft replenishing looms, as the shuttle may be used to advantage in other looms, the device by virtue of which the shuttle is self threaded adapting it for 105 convenient rethreading without danger to the operative by sucking the thread through the eye, and the spring bobbin holding jaws, while being especially adapted for use in weft replenishing looms, may be used in 110 connection with other looms.

Having thus described my present invention, what I claim is:

1. A self-threading shuttle, having a threading block provided with a leftwardly, 115 downwardly and inwardly inclined shield, a slot for admitting the thread into the block and a horn conforming externally with the outside contour of the block interposed in one end of the slot, for preventing the 120 thread from escaping up through the slot.

2. A self-threading shuttle having a cylindrical threading block provided with a leftwardly, downwardly and inwardly inclined shield, a spiral slot in the top of the block, 125 a curved horn interposed in one end of the slot, a delivery eye and a delivery eye slot.

3. A self-threading shuttle having a threading block provided on the left-hand end of its outer side with an upright which 130

has a downwardly and backwardly receding deflector on its left-hand end, a delivery eye in the threading block, and a delivery eye slot communicating between the bottom end 5 of the deflector and the delivery eye.

4. A self-threading shuttle having a cylindrical threading block provided with a downwardly, leftwardly and inwardly inclined shield, an upright on the left-hand 10 outer side of the block for supporting the shield, a downwardly and backwardly receding deflector on the left-hand end of the upright, a delivery eye in the outer wall of the cylindrical threading block and a delivery 15 eye slot communicating between the bottom end of the deflector and the delivery eye.

5. A self-threading shuttle having a cylindrical threading block provided with a tubular chamber, a spiral slot in the top of the 20 block, a delivery eye, a guide pin interposed vertically in the left-hand end of the tubular chamber and adjacent to the delivery eye, and a delivery eye entrance slot formed in the bottom of the block leading from the 25 tubular chamber to the delivery eye.

6. A self-threading shuttle having a cylindrical threading block provided with a tubular thread chamber, a guide pin interposed vertically in the left-hand end of the tubular 30 chamber, a spiral thread entrance slot in the top of the block, a curved horn in the right-hand end of the spiral slot, a shield inclined downwardly, leftwardly and inwardly, an upright on the left-hand end of the outer 35 wall of the block for supporting the shield, an inwardly curved beak terminating the shield, a downwardly and backwardly receding deflector on the left-hand end of the upright, a delivery eye, and a delivery eye 40 slot.

7. A self-threading shuttle having a cylindrical threading block, a spiral thread entrance slot in the threading block and a diagonally spiral thread channel leading 45 from the top of the shuttle to the threading block and registering with the spiral slot whereby a thread may be drawn down into the threading block.

8. A self-threading shuttle having a cylindrical threading block, a spiral thread entrance slot in the threading block, a diagonally spiral thread channel leading from the top of the shuttle to the threading block and registering with the spiral thread slot, 55 and a shield having a beak overhanging the thread channel whereby a filling thread may be drawn down into the threading block and prevented from repassing through the thread channel.

60 9. A self-threading shuttle having a cylindrical threading block, a spiral thread entrance slot in the threading block, a diagonally spiral thread channel leading from the top of the shuttle to the threading block 65 and registering with the spiral thread slot,

whereby the filling may be drawn into the threading block and prevented from repassing from the threading block.

10. A self-threading shuttle having a cylindrical threading block, a slot in the 70 block, a channel in the shuttle leading into the slot, a leftwardly, downwardly and inwardly inclined shield to deflect the thread into the slot, an upright supporting the shield and connecting with the left-hand end 75 of the thread block, a beak depending from the shield and a recess in the shuttle having edges projecting outward laterally beyond the beak, the beak and the edges of the recess co-operating to prevent the thread from 80 escaping up over the shield.

11. A self-threading shuttle having a cylindrical threading device having a thread chamber, a spiral slot in the threading device, affording thread entrance into the 85 thread chamber, a delivery eye for controlling the delivery of the thread, and a delivery eye slot for leading the thread from the thread chamber to the delivery eye.

12. A self-threading shuttle having a 90 cylindrical threading device having a thread chamber, a spiral slot in the threading device affording thread entrance into the thread chamber, a delivery eye for controlling the delivery of the thread, and a delivery eye slot formed in the bottom of the 95 threading device for leading the thread from the thread chamber to the delivery eye.

13. A self-threading shuttle for automatic looms, having a threading block including 100 a temporary thread delivery passage, a channel in the delivery end of the shuttle, and a slot in the threading block giving into the delivery passage and registering with the channel, the temporary thread delivery 105 passage occupying a low position relatively to the ends of the tines of the detector fork so that the filling thread on the first pick of the shuttle after filling replenishment, will engage the detector fork near the ends of 110 the tines.

14. A self-threading shuttle for automatic looms, having a threading block, including a thread chamber and a delivery eye, the thread chamber constituting a temporary 115 delivery passage low relatively to the ends of the tines of the detector fork when the thread is not drawn through the delivery eye, and an ultimate thread delivery passage when the thread is drawn through the 120 delivery eye, so as to cause the thread to be delivered from substantially the same planes in temporary and ultimate delivery positions.

15. A self-threading shuttle having at its 125 thread delivery end a cylindrical threading block provided with a thread chamber, an entrance into the chamber, a delivery eye at the forward outer end of the block, a concavo-convex shelf constituting the lower 130

- forward end of the thread block, and a delivery eye slot situated rearwardly of the shelf and communicating between the thread chamber and the delivery eye.
- 5 16. A self-threading shuttle having a spirally formed channel in one end, and a threading block provided with a leftwardly, downwardly, and inwardly inclined shield, a slot in the top of the block registering 55 with the shuttle channel for admitting the thread into the block, and a horn in one end of the slot for permitting the thread to be drawn down through the slot into the block, and for preventing the thread from 60 escaping up through the slot.
17. A self-threading shuttle having a diagonally spiral thread channel leading from the top of the shuttle downwardly, said channel being divergent at one end and 65 convergent at the other, in combination with a cylindrical threading block having a tubular thread chamber and a spiral thread entrance slot therein giving into the tubular thread chamber and in registration with 70 the thread channel, said threading block and said shuttle having coöperating parts overlapping each other forward of the point where the thread channel converges to permit a thread to be drawn down into the 75 threading block and to prevent its egress therefrom.
18. A self-threading shuttle having a cylindrical threading block provided with a tubular thread chamber, having provision 80 for delivering the thread directly therefrom, a spiral thread entrance slot in the top of the block, a downwardly directed horn in one end of the spiral slot, an upright on the outer wall of the block at the 85 end opposite the horn, a shield on the upright having an inwardly curved beak terminating it, a delivery eye, and a delivery eye slot, said tubular thread chamber being on substantially the same plane with 90 the delivery eye so that the thread may be delivered on substantially the same plane from either the tubular thread chamber or the delivery eye.
19. A self-threading shuttle having a cylindrical threading block provided with a 95
- leftwardly, downwardly, and inwardly inclined shield, a tubular thread chamber in the block, having provision for delivering the thread directly therefrom, a spiral slot in the top of the block, a curved horn interposed in one end of the slot, a delivery eye, and a delivery eye slot, the tubular thread chamber and the delivery eye being constructed and arranged so that, when the thread is being delivered from either the 60 one or the other it is on substantially the same plane.
20. A self-threading shuttle having a cylindrical threading block, a tubular thread chamber in the block, a thread entrance slot 65 in the top of the block, a curved horn in one end of the slot to prevent the egress of the thread from the tubular thread chamber, a downwardly and inwardly inclined shield formed at the end of the block opposite to 70 the horn, a delivery eye, a delivery eye slot, and a passageway between the forward bottom end of the block and the adjacent part 75 of the shuttle permitting the thread to pass from the tubular chamber into the delivery eye slot.
21. A self-threading shuttle having a cylindrical threading block provided with a downwardly and inwardly inclined shield, a thread chamber in the block, a spiral slot 80 in the top of the block, a curved horn in one end of the slot, a shed formed on the top of the block and situated beneath one end of the shield for deflecting the thread into the spiral slot, a delivery eye, and a 85 delivery eye slot affording passageway for the thread from the chamber to the delivery eye.
22. A self-threading shuttle having a diagonally spiral thread channel divergent 90 at its right-hand end and convergent at its left-hand end, and a recess in its wall, in combination with a threading block having a downwardly and inwardly inclined shield provided with a curved beak adapted to 95 project into the recess.
